UNITED STATES PATENT OFFICE.

WILLIAM H. DOUGLAS, OF WASHINGTON, DISTRICT OF COLUMBIA.

DESIGN FOR A TANK FOR FIRE-EXTINGUISHERS.

SPECIFICATION forming part of Design No. 32,600, dated June 5, 1900.

Application filed April 28, 1900. Serial No. 14,768. Term of patent 14 years.

To all whom it may concern:

Be it known that I, WILLIAM H. DOUGLAS, a citizen of the United States, residing at Washington, in the District of Columbia, have 5 invented and produced a new and original Design for Tanks for Fire-Extinguishers, of which the following is a specification, reference being had to the accompanying drawing, forming part thereof, in which is shown in 10 side elevation my new design.

As shown in the drawing, the leading or material feature of my design consists of the seamless cylindrical body A, the curved or rounded top B, the ribs or beads C, D, E, 15 and F, and the deep corrugation or flaring groove G, the said rib C encircling the body at the rib D near the bottom of the body, the space between said ribs being left plain. The

ribs E and F are smaller than the ribs C and D, and said rib E is arranged immediately 20 adjacent the rib D, and the rib F is disposed around the bottom, the groove or corrugation being between said ribs E and F.

Having described my invention, what I claim as new, and desire to secure by Letters 25 Patent, is—

The design for a tank for a fire-extinguisher as herein shown and described.

In testimony whereof I have signed my name to this specification in the presence of 30 two subscribing witnesses.

WILLIAM H. DOUGLAS.

Witnesses:

CHARLES F. HALE,
GEO. E. TERRY.
